(57) **CLAIM**

The ornamental design for an air delivery conduit for positive airway pressure delivery console, as shown and described.

DESCRIPTION

FIG. 1 is a rear perspective view of an air delivery conduit for positive airway pressure delivery console showing our new design in a first embodiment;

FIG. 2 is an enlarged perspective view thereof in a disconnected condition;

FIG. 3 is an enlarged rear perspective view thereof, showing the connector cuff in isolation;

FIG. 4 is a top view thereof;

FIG. 5 is a bottom view thereof;

FIG. 6 is a left side view thereof;

FIG. 7 is a right side view thereof;

FIG. 8 is a front view thereof;

FIG. 9 is a rear view thereof;

FIG. 10 is a front perspective view thereof;

FIG. 11 is a rear perspective view of an air delivery conduit for positive airway pressure delivery console showing our new design in a second embodiment;

FIG. 12 is an enlarged perspective view thereof in a disconnected condition;

FIG. 13 is an enlarged rear perspective view thereof, showing the connector cuff in isolation;

FIG. 14 is a top view thereof;

FIG. 15 is a bottom view thereof;

FIG. 16 is a left side view thereof;

FIG. 17 is a right side view thereof;

FIG. 18 is a front view thereof;

FIG. 19 is a rear view thereof; and,

FIG. 20 is a front perspective view thereof.

The broken lines in FIGS. 1, 2, 11, and 12 depict environmental structure that forms no part of the claimed design. All other broken lines depict portions of the air delivery conduit for positive airway pressure delivery console that form no part of the claimed design.
